MINING MACHINE

Frank A. Lindgren, Western Springs, Ill., assignor
to Goodman Manufacturing Company, Chi-
cago, Ill., a corporation of Illinois

Application March 13, 1931, Serial No. 522,236
Renewed January 10, 1935

21 Claims. (Cl. 262—28)

This invention relates to improvements in mining machines and more particularly to mining machines of the shearing type adapted to cut a vertical kerf in a mine wall at various angles with respect thereto including a vertical kerf at right angles to the mine track.

My invention has among other objects to provide a new and improved mining machine of the shearing type of a low compact design having a pivotally mounted cutter bar movable about a horizontal axis and movable on guides into and out of the coal and having frictionally controlled plural speed drive means for feeding the cutter bar into the coal and retracting said cutter bar therefrom, and for vertically moving the cutter bar in the coal about a transverse axis.

Other objects of my invention will appear from time to time as this specification proceeds.

My invention may be more clearly understood with reference to the accompanying drawings wherein:

Figure 1 is a side elevation of one embodiment of my invention in position to make a vertical cut in the mine wall parallel with the mine track;

Figure 2 is a side elevation of the device shown in Figure 1 in position to make a vertical cut in the mine wall at right angles to the mine track;

Figure 3 is a partial fragmentary plan view of the device shown in Figure 1 with parts broken away and in section to more clearly show the details of my invention;

Figure 4 is a partial fragmentary side elevation of the device shown in Figure 1 with parts broken away and in section to more clearly show the details of my invention;

Figure 5 is a partial sectional view taken on line 5—5 of Figure 3;

Figure 6 is an enlarged partial longitudinal section taken on line 6—6 of Figure 3; and

Figure 7 is an enlarged detail sectional view showing a detail of the means for holding the holding jacks to the machine frame.

Like numerals refer to like parts throughout the various figures.

Referring now in particular to the embodiment of my invention illustrated in the drawings, 10 indicates a truck supported on track wheels 11 and axles 12. The truck 10 is provided with a vertical bearing 13 midway between the truck axles 12 on the longitudinal center line of said truck for receiving a bearing member 14 depending from and attached to a turntable 15.

The turntable 15 has a pair of vertically disposed parallel spaced guide bars 17 fixed to the top portion thereof in a suitable manner; as, for

instance, angle irons and rivets as is illustrated in Figure 5. The parallel spaced guide bars 17 extend forwardly and rearwardly of the turntable 15 and extend forwardly beyond the truck 10 to provide a slidable support for a cutting 5 element 18.

The cutting element 18 includes a vertically disposed cutter bar 19 pivotally supported thereon for movement about a horizontal axis adjacent its rearward end and a motor 20 for moving said cutting element along the parallel spaced bars 17, for vertically moving the cutter bar about its horizontal axis and for driving a cutter chain 21 about said cutter bar in a usual manner. The motor 20 may be of any type well known to the art but is herein preferably shown as being an electric motor.

The cutting element 18 is supported on the parallel spaced guide bars 17 for reciprocable sliding movement therealong. Said guide bars have a 20 relatively wide top surface to provide a firm slid- 20 able support for said cutting element and are relatively wide to accommodate guide mem- bers 23.

The cutting element 18 includes a frame mem- 25 ber 25. The guide members 23 are fixed to the frame member 25 adjacent opposite ends thereof and extend outwardly from each side thereof. The guide members 23 may be fixed to the frame member 25 in any suitable manner but are here- 30 in preferably shown as being bolted to said frame member. These guide members have bearing sup- port on the top surface of the parallel spaced 35 guide bars 17 and extend downwardly along the outer side of said guide bars and are provided with inwardly extending projections 26 which engage 35 a portion of the under surface of said guide bars to prevent tilting movement of the cutting ele- 40 ment 18 with respect to the turntable 15.

A horizontal rack 27 extends inwardly from 40 each guide bar 17. This rack is of an ordinary construction well known to those skilled in the art so will not be described in detail and is en- gaged by sprockets 29 on opposite sides of the cutting element 18 keyed to opposite ends of a 45 horizontal shaft 30. The horizontal shaft 30 is journaled in the frame member 25 and may be selectively driven by the motor 20 in reverse directions without reversal of said motor at a plurality of predetermined frictionally controlled 50 speeds in a manner which will hereinafter be de- scribed.

The cutter bar 19 is mounted on a support mem- 55 ber 31 for pivotal movement about a trans- verse axis. The support member 31 is provided

with a hub 32 at one side, which hub is freely mounted on a horizontally disposed sleeve 33 and the outer surface of said hub is journaled in a bearing member 35 fixed to the frame member 5 25. The support member 31 encloses a cutter chain drive sprocket 36 keyed on the horizontally disposed sleeve 33 and has a side opposite the side journaled in the bearing member 35 keyed on a spider 37. Said spider is freely mounted on the 10 horizontally disposed sleeve 33 adjacent the opposite side of the cutter chain drive sprocket 36 from the hub 32. The outer portion of said support adjacent said spider is journaled in a bearing support 38 so said support member and the 15 cutter bar 19 may be moved about the axis of the cutter chain drive sprocket 36.

Means are provided for vertically moving the cutter bar 19 about the axis of the cutter chain sprocket 36, which means herein comprises a 20 rearwardly facing arcuate rack 39 keyed on an outwardly extending portion 40 of the support member 31. This arcuate rack is engaged by a spur pinion 41 keyed on the end of a transversely extending shaft 43 journaled within a bearing support 44 on the frame member 25. A worm gear 45 is keyed on the transversely extending shaft 43 and is driven by a worm 47 on a longitudinally extending shaft 48. The shaft 48 has selective connection with the motor 20 and may be driven 25 therefrom at a plurality of frictionally controlled speeds in a manner which will hereinafter be more fully described.

The worm 47 and worm gear 45 are of the self-locking type so the cutter bar 19 may be held in 30 any desired vertical position with respect to the truck 10.

The outwardly extending portion 40 of the support member 31 has slidable engagement with an arcuately shaped upwardly extending guide portion 49 of the frame member 25. A retaining strip 50 is provided on the upwardly extending portion 49 of the frame member 25 to engage a portion 51 of the outwardly extending portion 40 of the support member 31 to prevent lateral movement of the cutter bar 19 and disengagement of the spur pinion 41 with the arcuate rack 39.

The cutter chain drive sprocket 36 is driven from the motor 20 in the following manner:

A motor pinion 53 meshes with and engages an 50 idler gear 54 on a shaft 55 journaled in bearing supports 56 integral with the frame member 25. The idler gear 54 meshes with and drives a spur gear 57 keyed on the outer end of a transversely extending shaft 58 freely mounted within the 55 sleeve 33 and extending outwardly therefrom and having its opposite end journaled in the frame member 25.

Means are provided for selectively connecting the cutter chain sprocket 36 with the spur gear 60 60 57 to drive the cutter chain 21 about the cutter bar 19 which means herein comprise a clutch collar 59 feathered on the hub of the spur gear 57 having clutch jaws 60 integral therewith adapted to engage clutch jaws 61 on the sleeve 65 33. It should be noted that the clutch collar 59 is so mounted on the hub of the spur gear 57 that the clutch jaws 60 extend through said spur gear and engage the jaws 61 on the opposite side 70 of said spur gear from the clutch collar 59. The clutch collar 59 is moved along the hub of the spur gear 57 to engage the clutch jaws 60 with or disengage said clutch jaws from the clutch jaws 61 to selectively drive the cutter chain drive 75 sprocket 36 from the motor 20 by means of a suit-

able system of levers in a usual manner not herein shown.

Referring now to several of the novel features of my invention and the means for reciprocably moving the cutting element 18 along the parallel spaced guide bars 17 at a plurality of predetermined frictionally controlled speeds without reversal of the motor and to the means for moving the cutter bar about the axis of the cutter chain sprocket 36 at a plurality of predetermined frictionally controlled speeds, a worm 62 is cut integral with the transversely extending shaft 58 and meshes with and drives a worm gear 63 keyed on a sleeve 64, which sleeve is freely mounted on a longitudinally extending shaft 65. A hub 66, 10 15 of a casing 67 of a planetary gear mechanism 68, is freely mounted on the sleeve 64 and journaled within a portion of a casing and bearing support for the worm 62 and worm gear 63. The sleeve 64 extends within the casing 67 of the planetary gear mechanism 68 and has a sun gear 69 cut integral therewith. The sun gear 69 meshes with planetary pinions 70 mounted on shafts 71 supported at their ends in a cage 72. The planetary pinions 70 mesh with an internal gear 73 20 25 30 keyed to the inner periphery of the casing 67. Planetary pinions 75 are cut integral with the planetary pinions 70 and are adjacent and coaxial with said pinions and mesh with an internal gear 76 freely mounted within the inner periphery of the casing 67.

The internal gear 76 is provided with clutch jaws 77. A clutch sleeve 78 is feathered on the longitudinally extending shaft 65 and is provided with clutch jaws 79 adapted to mesh with the clutch jaws 77 for driving said shaft from the internal gear 76 at a low speed. Similarly the cage 72 has a member 80 keyed thereto which surrounds the shaft 65 and is provided with clutch jaws 81 for driving the shaft 65 at a high frictionally controlled speed through the cage 72.

Frictional control of the planetary gear reduction mechanism 68 is effected by means of a friction band 83 which surrounds the outer periphery of the casing 67. Said friction band is 45 tightened or allowed to loosely engage the casing 67 to vary the point at which the casing will slip within said band by means of a hand wheel 84 threaded on a rod 85. One end of the rod 85 engages one end of the friction band 83 while the 50 hand wheel 84 abuts a lug 86 fixed to the opposite end of said friction band so rotation of said hand wheel in one direction will tighten the friction band on the casing 67 and rotation of said hand wheel in an opposite direction will allow 55 said friction band to loosely engage said casing.

It will thus be seen that when the friction band engages the casing 67 the internal gear 73 is held stationary and the internal gear 76 and cage 72 are rotated at a high rate of speed due to the 60 orbital travel of the planetary pinions 70 about the internal gear 73, while when said friction band loosely engages the casing 67, said internal gear and cage are rotated at a lower rate of speed due to slippage of the internal gear 73 and casing 65 67 within the friction band 83. It may also be seen that when undue loads or stresses are imposed upon either the internal gear 76 or the cage 72, the casing 67 will slip within the friction band 83 which will slow the speed of rotation of said 70 internal gear or cage and serve as a safety means to prevent breakage of the various parts of the feeding or cutter bar rotating mechanism.

Thus the shaft 65 may be driven at a predetermined frictionally controlled low speed through 75

the internal gear 76, clutch jaws 77 and clutch jaws 79 on the clutch sleeve 78 or at a predetermined frictionally controlled higher speed through the cage 72, clutch jaws 81 and clutch jaws 79 on the clutch sleeve 78. The clutch sleeve is shifted along the shaft 65 to engage the clutch jaws 79 with either the clutch jaws 77 or clutch jaws 81 by means of a clutch yoke 88 and a suitable system of levers in a usual manner (not shown).

A clutch sleeve 89 is feathered on the forward end of the longitudinally extending shaft 65. This clutch sleeve is provided with a flange 90 at its rearward end, which flange is provided with apertures 91 adapted to engage clutch jaws 92 extending rearwardly from the face of a spur gear 93 freely mounted on said clutch sleeve and journaled on its hub in a bearing member 94 integral with the frame member 25. Said clutch sleeve is moved along the shaft 65 to engage or disengage the apertures 91 with the clutch jaws 92 by means of a suitable system of levers in a usual manner. The spur gear 93 meshes with and drives a spur gear 95 keyed on the longitudinally extending shaft 48 for driving said shaft and the worm 47 and thus driving the spur pinion 41 and vertically moving the cutter bar about the axis of the cutter chain sprocket 36. Thus the cutter bar may be vertically moved about the axis of the cutter chain sprocket 36 at either a high or low frictionally controlled speed through the planetary gear reduction mechanism 68.

Referring now in particular to the means for reciprocably moving the cutting element 18 along the parallel spaced guide bars 17 at a plurality of predetermined frictionally controlled speeds without reversal of the motor, a sleeve 97 is keyed to the rearward end of the longitudinally extending shaft 65 and is journaled in the frame member 25. A bevel pinion 98 is cut integral with the rearward end of the sleeve 97 and meshes with and drives oppositely disposed bevel gears 99 and 100. The bevel gears 99 and 100 are journaled on their hubs in a casing 101 integral with the frame member 25 and are freely mounted on the transverse shaft 30. A clutch collar 103 is feathered on the horizontal shaft 30 between the bevel gears 99 and 100 and has clutch jaws 104 on opposite sides thereof. These clutch jaws are adapted to engage clutch jaws 105 on the bevel gear 99 or clutch jaws 106 on the bevel gear 100 for driving the shaft 30 in opposite directions without reversal of the motor in an obvious manner. The clutch collar 103 is shifted along the shaft 30 to drive said shaft from either of the bevel gears 99 or 100 in a usual manner not herein shown or described in detail. Thus the cutting element 18 may be moved along parallel spaced guide bars 17 and racks 21 in opposite directions at either a high or low predetermined frictionally controlled speed without reversal of the motor.

Means are provided to hold the turntable 15 and parallel spaced guide bars 17 steady during the cutting operation which comprise a plurality of jacks 107 detachably connectible with the outer sides of the guide bars 17 adjacent the forward end thereof and a plurality of jacks 109 detachably connectible with the rearward end of the truck 10 at opposite sides thereof. The jacks 107 and 109 are of a usual type of screw jack well known to those familiar with the art, which may be interposed between the mine roof and mine bottom and tightened against the mine roof and bottom by means of a suitable hand wheel or any other screw operating means. Said

jacks 107 or 109 may be connected to the outer sides of the guide bars 17 or truck 10 in any suitable manner but as herein shown these jacks are adapted to pass through sockets 110. Each socket 110 has a pin 111 extending inwardly therefrom adapted to be placed in a member 108 fixed to each guide bar 17 and opposite sides of the truck 10 so said socket may be pivotally moved with respect to the truck about a horizontal axis to position the jacks at varying angles with respect to the mine bottom. A nut is threaded on the inner end of each pin 111 and abuts the inner side of the member 108 to hold the socket 110 in the member 108. The jacks 109 and 107 are held in the sockets 110 by means of a bolt 112 threaded through each socket 110 and having a bearing member 113 on its inner end adapted to bear against the jack which may pass through said socket.

The truck 10 is propelled along the mine bottom to move the mining machine from working place to working place by means of a suitable gear train which includes a spur gear 115 driven by the motor pinion 53 and keyed on a transverse shaft 116 rearwardly of the motor 20. A bevel pinion 117 is keyed on the opposite end of said transverse shaft and meshes with and drives a bevel gear 118. The bevel gear 118 is journaled on its hub in the frame member 25 and has a shaft 119 keyed thereon. An outer end 120 of the shaft 119 is of rectangular cross section and is adapted to be engaged by a forked end 121 of a coupling pin 123. The rearward portion of the coupling pin 123 is of a rectangular cross section and is slidably mounted within the hub 35 of a worm 124 so that the forked end may engage the outer end 120 of the shaft 119 or be disengaged therefrom in a usual manner well known to those familiar with the art. The worm 124 is journaled within a bearing support and housing 40 125 and meshes with and drives a worm gear 126 on a transversely extending shaft 127. The transverse shaft 127 is journaled in the bearing support and housing 125 and bearing supports 129 fixed to the truck 10 and has sprockets 130 45 keyed on opposite ends thereof. The sprockets 130 have connection with the rearward track wheels 11 by means of suitable chain and sprocket drive 131. The forward and rearward track wheels 11 are operatively connected together by 50 means of suitable chain and sprocket drives 132 in the usual manner. Thus the track wheels 11 may be selectively connected with the motor 20 for driving said track wheels and moving the truck 10 and mining machine about the mine 55 from working place to working place.

Referring now in particular to Figures 1 and 2 and the use and operation of the device embodying my invention, it may be seen that in Figure 1 the cutting element is positioned for cutting a vertical kerf parallel to the mine rails. The jacks 107 and 109 are set at opposite sides of the guide bars 17 and the truck 10, respectively, for holding said guide bars and truck in a stationary position. The cutter bar 19 is positioned so the cutter chain bits are adjacent the mine roof. The motor 20 is started and the clutch jaws 60 are engaged with the clutch jaws 61 to drive the cutter chain sprocket 36 and thus drive the cutter chain 21 about the cutter bar 70 19. The cutting element is then moved forwardly along the guide bars 17 and racks 21 by means of the sprockets 29 at a slow frictionally controlled speed through the planetary reduction gear mechanism 68 and internal gear 76. When 75

the cutter bar has advanced into the coal the desired distance, said cutter bar is moved downwardly about the axis of the cutter chain sprocket 36 by means of the rack 39 and spur pinion 41 driven by the motor 20 through the frictionally controlled planetary gear device 68. When the cutter bits are adjacent the mine bottom, downward movement of the cutter bar 19 is stopped by means of disengaging the apertures 91 from the clutch jaws 92 and the cutter bar 19 and cutting element 18 may be moved rearwardly along the guide bars 17 at a frictionally controlled high or low speed obtained through the planetary gear reduction device 68, cage 72, or internal gear 76 and bevel gears 99 or 100 without reversal of the motor 20.

Figure 2 shows the cutter bar 19 in position to cut a kerf in the mine wall at right angles to the mine track. In order to cut such a kerf the turntable 15 is moved about the axis of the bearing member 14 and the jacks 107 and 109 are set between the mine roof and bottom and the cutting operation hereinbefore described is followed through. One purpose of mounting the cutting element 18 on a turntable is to permit the cutting of kerfs at right angles to the mine track or at various angles with respect thereto so a cut may be made along the entry and another cut may be made at various angles with respect to the entry for driving breakthroughs or cross-entries.

It may now be seen that a new and improved mining machine has been provided which is adapted to cut a vertical kerf in the mine wall parallel to the mine track or at various angles with respect thereto and that this cutting element is movable along an extended guide frame at a plurality of predetermined frictionally controlled speeds. It may also be seen that when the cutter bar has been moved into the coal the required distance, that this cutter bar may be moved about a horizontal axis to cut vertically in the coal at a plurality of predetermined frictionally controlled speeds. Thus a shearing machine has been provided which has means incorporated therewith to compensate for rock or hard spots encountered in the coal, which means is effective both while the cutter bar is being sumped or driven into the coal and while the cutter bar is cutting vertically downwardly or upwardly in the coal. This prevents breakage of the drive parts for the cutter chain or feeding mechanism and eliminates the tendency of the machine to jump out of the coal when hard spots or rock are encountered. It may also be seen that this mechanism is effective at both high and low speeds which permits a variety of frictionally controlled speeds to be used in cutting and permits the machine to either cut slowly where the coal is hard or cut faster where the coal is soft and enables the machine to be readily positioned for cutting or returned to a travelling position on the truck. It may also be seen that this machine is of a low compact design and is so arranged that the cutter bar is rigidly supported adjacent the coal face during the vertical cutting operation.

While I have herein shown and described one form in which my invention may be embodied, it will be understood that the construction and arrangement of the various parts may be altered or changed without departing from the spirit and scope thereof. Furthermore, I do not wish to be construed as limiting myself to the particular

form illustrated, excepting as it may be limited in the appended claims.

I claim as my invention:

1. In a mining machine of the class described, a truck mounted on track wheels and axles for movement along a mine track, a cutting element supported on said truck for reciprocable slidable movement with respect thereto comprising a vertically disposed pivotally mounted cutter chain carrying cutter bar, and a single frictionally controlled plural speed gear reduction mechanism having operative connection with said cutter bar and cutting element for moving said cutter bar about its pivotal axis and independently reciprocably moving said cutting element with respect to said truck. 5 10 15

2. In a mining machine of the class described, a truck mounted on track wheels and axles for movement along a mine track, a cutting element supported on said truck for pivotal movement 20 about a vertical axis and for reciprocable slidable movement with respect thereto in a horizontal plane comprising a cutter chain carrying cutter bar mounted for swinging movement about a transverse horizontal axis, and plural speed 25 means for moving said cutter bar about its pivotal axis and reciprocably moving said cutting element with respect to said truck comprising a plural speed planetary gear reduction mechanism. 30

3. In a mining machine of the class described, a truck mounted on track wheels and axles for movement along a mine track, a cutting element supported on said truck for pivotal movement about a vertical axis and for reciprocable slidable movement with respect thereto in a horizontal plane comprising a cutter chain carrying cutter bar mounted for swinging movement about a transverse horizontal axis, and frictionally controlled plural speed means having a geared connection 35 40 with said cutter bar and cutting element for moving said cutter bar about its pivotal axis and reciprocably moving said cutting element with respect to said truck comprising a frictionally controlled plural speed planetary gear reduction mechanism. 45

4. In a mining machine of the class described, a truck mounted on track wheels and axles for movement along a mine track, a cutting element supported on said truck for reciprocable slidable movement with respect thereto comprising a motor, a vertically disposed cutter chain carrying cutter bar mounted for pivotal movement about a horizontal axis disposed adjacent its rearward end, and a single frictionally controlled plural speed means driven by said motor, a geared connection from said plural speed means for moving said cutter bar about said pivotal axis and another geared connection from said plural speed means for independently reciprocably moving said cutting element with respect to said truck without reversal of said motor. 50 55 60

5. In a mining machine of the class described, a truck mounted on track wheels and axles for movement along a mine track, a cutting element supported on said truck for pivotal movement about a vertical axis and for reciprocable slidable movement with respect thereto comprising a motor, a cutter chain carrying cutter bar mounted for swinging movement in a vertical 70 plane about an axis disposed adjacent its rearward end, and a single frictionally controlled plural speed means driven by said motor, a drive connection from said plural speed means to said cutter bar for moving said cutter bar about said 75

- 5 pivotal axis and another drive connection from said plural speed means for independently reciprocably moving said cutting element with respect to said truck without reversal of said motor.

6. In a mining machine of the class described, a truck mounted on track wheels and axles for movement along a mine track, a cutting element supported on said truck for pivotal movement about a vertical axis and for reciprocable

10 slidable movement with respect thereto comprising a motor, a cutter chain carrying cutter bar mounted for pivotal movement in a vertical plane about an axis disposed adjacent its rearward end, a single plural speed planetary gear reduction

15 device, a drive connection from said planetary gear reduction device to said cutter bar for moving said cutter bar about said pivotal axis and another drive connection from said planetary gear reduction device to said truck for independently reciprocably moving said cutting element with respect to said truck without reversal of said motor.

20 7. In a mining machine of the class described, a truck mounted on track wheels and axles for movement along a mine track, a cutting element supported on said truck for reciprocable slidable movement with respect thereto comprising a motor, a cutter chain carrying cutter bar mounted for vertical swinging movement about a horizontal axis disposed adjacent its rearward end, and a single frictionally controlled plural speed means driven by said motor for reciprocably moving said cutting element with respect to said truck without reversal of said motor and moving said cutter

25 bar about its axis of pivotal connection to said truck comprising a frictionally controlled plural speed planetary gear reduction mechanism.

30 8. In a mining machine of the class described, a truck mounted on track wheels and axles for movement along a mine track, a turntable mounted on said truck, a frame member mounted on said turntable and extending beyond the extremities thereof, a cutting element supported on said

35 frame member for movement therealong comprising a motor, a vertically disposed chain carrying cutter bar mounted for pivotal movement about a horizontal axis, and a single frictionally controlled plural speed gear reduction device driven by said motor for moving said cutter bar about said horizontal axis or reciprocably moving said cutting element along said frame member.

40 9. In a mining machine of the class described, a truck mounted on track wheels and axles for movement along a mine track, a turntable mounted on said truck, a frame member mounted on said turntable and extending beyond the extremities thereof, a cutting element supported on said

45 frame member for movement therealong comprising a motor, a vertically disposed chain carrying cutter bar mounted for pivotal movement about a horizontal axis, and a single frictionally controlled plural speed gear reduction device driven by said motor for moving said cutter bar about said horizontal axis or reciprocably moving said cutting element along said frame member.

50 10. In a mining machine of the class described, a truck mounted on track wheels and axles for movement along a mine track, a turntable mounted on said truck, a frame member mounted on said turntable and extending beyond the extremities thereof, a cutting element supported on said

55 frame member for movement therealong comprising a motor, a chain carrying cutter bar mounted for pivotal movement about an axis disposed adjacent its rearward end and perpendicular to its cutting plane and plural speed means for moving said cutter bar about said pivotal axis or reciprocably moving said cutting element with respect to said truck comprising a single plural speed planetary gear reduction mechanism.

60 11. In a mining machine of the class described, a truck mounted on track wheels and axles for movement along a mine track, a turntable mounted on said truck, a frame member mounted on said turntable and extending beyond the extremities thereof, a cutting element supported on said

65 frame member for movement therealong comprising a motor, a vertically disposed chain carrying cutter bar mounted for pivotal movement about a horizontal axis, plural speed means for

70 12. In a mining machine of the class described, a truck mounted on track wheels and axles for movement along a mine track, a turntable mounted on said truck, a frame member mounted on said turntable and extending beyond the extremities thereof, a cutting element supported on said

75 frame member for movement therealong comprising a motor, a vertically disposed chain carrying cutter bar mounted for pivotal movement about a horizontal axis, plural speed means for

moving said cutter bar about said pivotal axis or reciprocably moving said cutting element with respect to said truck including a single plural speed planetary gear reduction mechanism and self-locking means for holding said cutter bar in various angular positions with respect to said frame member.

15. In a mining machine of the class described, a truck mounted on track wheels and axles for movement along a mine track, a turntable mounted on said truck, a frame member mounted on said turntable and extending beyond the extremities thereof, a cutting element supported on said frame member for movement therealong comprising a motor, a vertically disposed chain carrying cutter bar mounted for pivotal movement about a horizontal axis, frictionally controlled plural speed means driven by said motor for moving said cutter bar about said horizontal axis and independently reciprocably moving said cutting element along said frame member without reversal of said motor comprising a single frictionally controlled plural speed planetary gear reduction mechanism, reversing mechanism interposed between said planetary gear mechanism and the drive means for reciprocably moving said cutting element along said frame member, and self-locking drive gearing for moving said cutter bar about said pivotal axis or holding said cutter bar in various angular positions with respect to said frame member.

16. In a mining machine of the class described, a truck mounted on track wheels and axles for movement along a mine track, a cutting element supported on said truck for reciprocable slidable movement with respect thereto comprising a motor, a vertically disposed cutter chain carrying cutter bar mounted for pivotal movement about a horizontal axis adjacent its rearward end, a single frictionally controlled plural speed gear reduction means driven by said motor and having operative connection with said cutter bar and cutting element for moving said cutter bar about said pivotal axis and independently reciprocably moving said cutting element with respect to said truck, and self-locking means for holding said cutter bar in various angular positions with respect to said truck.

17. In a mining machine of the class described, a track-mounted truck, a cutting element supported on said truck for reciprocable slidable movement with respect thereto comprising a motor, a cutter bar disposed forwardly thereof and pivotally movable in a vertical plane, self-locking mechanism driven by said motor for vertically swinging said cutter bar, and mechanism for feeding said cutter bar with respect to said truck comprising a rack on said truck, a pinion meshing therewith and a frictionally controlled plural speed geared reduction drive driven by said motor and having driving connection with said pinion.

18. In a mining machine of the class described, a track-mounted truck, a cutting element supported on said truck for reciprocable movement with respect thereto comprising a motor, a cutter bar disposed forwardly thereof and pivotally movable with respect thereto in a vertical plane, self-locking mechanism driven by said motor for swinging said cutter bar, and mechanism for feeding said cutter bar with respect to said truck comprising a rack on said truck, a pinion meshing therewith and plural speed means for recip-

rocably moving said cutting element with respect to said truck comprising a plural speed planetary geared reduction device driven by said motor and having selective connection with said pinion.

19. In a mining machine of the class described, a track-mounted truck, a cutting element supported on said truck for reciprocable movement with respect thereto comprising a motor, a cutter bar disposed forwardly thereof and pivotally movable with respect thereto in a vertical plane, self-locking mechanism driven by said motor for swinging said cutter bar, and mechanism for feeding said cutter bar with respect to said truck comprising a rack on said truck, a pinion meshing therewith and frictionally controlled plural speed means for reciprocably moving said cutting element with respect to said truck comprising a frictionally controlled plural speed planetary geared reduction device driven by said motor and having selective driving connection with said pinion.

20. In a mining machine, a track-mounted truck, and shearing cutting mechanism mounted on said truck including a frame rectilinearly movable along said truck, a cutter chain carrying cutter bar mounted on said frame for movement therewith and for pivotal movement about a horizontal transverse axis, a motor on said frame, and drive connections from said motor for moving said cutting mechanism along said truck, pivotally moving said cutter bar in a vertical plane and driving said cutter chain about said cutter bar comprising a shaft coaxial with the pivotal axis of said cutter bar for driving said cutter chain, a plural speed gear reduction mechanism coaxial with a shaft perpendicular to said last-mentioned shaft and extending in parallel relation with said cutter bar, a drive connection from said first-mentioned shaft to said gear reduction mechanism, a selective drive connection from said gear reduction device to said last-mentioned shaft, a drive connection from one end of said last-mentioned shaft for rectilinearly moving said cutting mechanism and a drive connection from the opposite end of said shaft for pivotally moving said cutter bar at a feeding speed.

21. In a mining machine, a track-mounted truck, and shearing cutting mechanism mounted on said truck including a rectilinearly movable frame, a cutter chain carrying cutter bar mounted on said frame for movement therewith and for pivotal movement about a horizontal transverse axis, a motor on said frame, and drive connections from said motor for moving said cutting mechanism along said truck, pivotally moving said cutter bar in a vertical plane and driving said cutter chain about said cutter bar comprising a shaft coaxial with the pivotal axis of said cutter bar for driving said cutter chain, a shaft perpendicular to said shaft and a frictionally controlled planetary geared reduction device coaxial with said last-mentioned perpendicular shaft, a drive connection from said first-mentioned shaft to said planetary, a selective drive connection from said planetary to said last-mentioned perpendicular shaft, a drive connection from one end of said last-mentioned perpendicular shaft for rectilinearly moving said cutting mechanism, and a drive connection from the other end of said perpendicular shaft for pivotally moving said cutter bar at a feeding speed.
